UNITED STATES PATENT OFFICE.

MATT Q. CORBETT, WILLIAM E. HUFFMAN, AND CLARENCE F. ADAMS, OF DAYTON,
OHIO.

CAPTIVE BALLOON.

Application filed June 27, 1923. Serial No. 648,023.

To all whom it may concern:

Be it known that we, MATT Q. CORBETT, WILLIAM E. HUFFMAN, and CLARENCE F. ADAMS, citizens of the United States, residing at Dayton, in the county of Montgomery and State of Ohio, have invented certain new and useful Improvements in Captive Balloons, of which the following is a specification.

10 This invention relates to captive balloons.

The broad object of the present invention is to maintain the front or nose of the balloon in a hemispherical contour, irrespective of fluctuations in the internal pressure 15 of the aerostat.

A further object of the invention is to provide in a captive balloon, an aerostat which will have a kiting action so that it will maintain its altitude in air streams of widely 20 varying velocity.

Another object of the invention is to provide an aerostat of stream-line formation combined with means for preserving such formation of the aerostat irrespective of 25 the expansion and contraction of the gas with which the balloon is inflated.

With the above and other objects in view, the invention consists in the novel construction, combination and arrangement herein 30 fully described, shown and claimed.

In the accompanying drawings.

Figure 1 is a perspective view of the improved captive balloon.

Figure 2 is a vertical section through the 35 aerostat in line with the fore and aft axis thereof.

Figure 3 is an enlarged detailed view of the automatic pressure relief valve.

The improved captive balloon is designed 40 especially for use in government service as an aerial buoy or marker for aircraft or as an elevated datum point in survey work or in working out problems in triangulation. For commercial work the improved balloon 45 is designed to be used as a support for various kinds of apparatus, such for example as that used for spraying or powdering trees and the like, particularly in connection with insect extermination. It may, however, be 50 adapted to other uses when it is feasible or may be found practicable to use as a small balloon attached to an anchoring rope or cable.

Referring now to the drawings, the improved captive balloon embodies an aero-

stat adapted to be filled with any buoyant gas. The forward or nose portion 5 of the aerostat is hemispherical, while the after portion 6 is conoidal in formation. Thus a streamline formation is imparted to the 60 aerostat, giving the minimum resistance to the air stream while in use. Stabilizing fins 7 and 8 extend longitudinally of the outside of the aerostat to eliminate side swaying of the balloon and one or more tail cups 9 may 65 be arranged in trailing relation to the rear end of the aerostat to assist in holding the latter head to the wind.

Within the aerostat are internal elastic stays 10, any number of which may be used 70 according to the size of the balloon. Each of the stays 10 is attached at its forward extremity to the inside of the aerostat at a point 11 along the equatorial line thereof, while the other end portion of the stay has 75 two elastic branches 12 and 13. One of these branches extends rearwardly and is attached at a point 14 to the rear end part of the after portion of the aerostat. The points 14 are arranged in a circular series, leaving 80 within such circle a central zone 15 which is adapted to be projected outwardly as indicated by the line 16 or is permitted to bulge inwardly as indicated by the line 17. The tendency of the elastic stays is to draw the 85 zone 15 inwardly as indicated by the line 17. However, as the gas expands and the internal pressure increases, the elastic stays allow the zone 15 to be pressed outwardly toward the projecting position indicated by the line 16. The construction just described provides an aerostat of variable capacity.

The other branches 13 of the internal elastic stays 10 are fastened to the casing 18 of a pressure relief valve 19, controlling 90 an outlet passage 20 in the valve casing and normally held closed with a predetermined pressure by means of a spring 21 encircling the stem of the valve between the valve casing and a stop or annular shoulder 22 95 on the inner end of the valve stem. The branches 13 which are elastic, assist the other branches 12 in controlling the flexure of the zone 15 and maintain the rear part of the aerostat in symmetrical form as clearly indicated in Figure 2 of the drawings.

The captive rigging 23 to which the anchoring rope or cable 24 is attached, is shown as independent of the load rigging 25 which carries the load indicated at 26. The two 110

riggings 23 and 25 may however, be combined if so desired. The inflation sleeve 27 is tied with an elastic cord 28 of such strength and under such tension as to act 5 as an automatic relief for the internal pressure in the aerostat to keep the same from bursting under abnormal conditions.

When the balloon is filled or inflated, only 10 enough gas is introduced to inflate or fill out the head or nose section 5 and the after section 6, the rear part of which is left partially collapsed or bulged inwardly by the action of the elastic stays 10 and their branches 15 12 and 13. There is thus provided a flexible or variable capacity and the rear end portion of the aerostat may expand and contract with the expansion and contraction of the gas in the entire balloon, and therefore keep the nose or head of the balloon at all times 20 from cupping due to wind pressure. This cupping action of the wind, together with the fact that an ordinary spherical balloon 25 does not give a kiting effect, is the chief cause of trouble in keeping such a balloon from being blown to the ground when held captive by a suitable anchoring rope or cable.

We claim:

1. A captive balloon embodying a variable 30 capacity aerostat having a hemispherical nose portion, a conoidal after portion, and internal elastic stays attached to the rear part of said after portion and serving to flex said rear part inwardly to vary the cubical internal capacity.

2. A captive balloon embodying a variable 40 capacity aerostat having a hemispherical nose portion, a conoidal after portion, and internal elastic stays attached to the rear part of said after portion and serving to flex said rear part inwardly to vary the cubical internal capacity while maintaining the streamline form of the aerostat.

3. A captive balloon embodying a variable 45 capacity aerostat having a hemispherical nose portion, a conoidal after portion, and

internal elastic stays extending in a fore and aft direction and attached to the rear part of said after portion and serving to flex said rear part inwardly to vary the 50 cubical internal capacity.

4. A captive balloon embodying a variable capacity aerostat having a hemispherical nose portion, a conoidal after portion, and internal elastic stays attached to the 55 rear part of said after portion and serving to flex said rear part inwardly to vary the cubical internal capacity, said stays being attached at their forward extremities to the inside of the aerostat adjacent to the equatorial line of the nose portion.

5. A captive balloon embodying a variable capacity aerostat having a hemispherical nose portion, a conoidal after portion, and internal elastic stays attached to the 65 rear part of said after portion at points ranging in a circle around the longitudinal axis of the aerostat.

6. A captive balloon embodying a variable capacity aerostat having a hemispherical nose portion, a conoidal after portion, an automatic pressure relief valve in the center of the rear end of said after portion, and internal elastic stays extending in a 70 fore and aft direction and having branches, one of which is attached to said valve and another of which is attached to the rear part of said after section.

7. A captive balloon embodying a variable capacity aerostat having a hemispherical nose portion, a conoidal after portion, and internal elastic means operable on the rear end part of said after section to flex said part from an outwardly projecting 80 position to an inwardly bulging or reentrant 85 position to compensate for variation in internal pressure.

In testimony whereof we affix our signatures.

MATT Q. CORBETT.
